LIMIT SWITCH

William F. Dehn, Wauwatosa, Wis., assignor to Allen-
Bradley Company, Milwaukee, Wis., a corporation of
Wisconsin

Application October 10, 1955, Serial No. 38,306

Term of patent 14 years

(Cl. D26—13)

Fig. 1.

Fig. 2.

Fig. 3.

Fig. 4.

Fig. 5.

Fig. 1 is an isometric perspective view of a limit switch, showing my new design;

Fig. 2 is a front elevational view thereof;

Fig. 3 is a top plan view thereof;

Fig. 4 is a side elevational view thereof; and

Fig. 5 is a rear elevational view thereof.

I claim:

The ornamental design for a limit switch, as shown.
